SEWING MACHINE

Bernard T. Leveque, Wenham, Mass., assignor to
 United Shoe Machinery Corporation, Borough
 of Flemington, N. J., a corporation of New
 Jersey

Application April 19, 1939, Serial No. 268,708

42 Claims. (Cl. 112—36)

The present invention relates to hook needle lockstitch sewing machines, and is herein disclosed as embodied in a shoe sole sewing machine of the so-called McKay type, similar in certain respects to the machine illustrated and described in the present inventor's prior U. S. Letters Patent 1,885,927 dated November 1, 1932. The needle of machines of this type is straight and the work support consists of a rotatable horn arranged to extend within a shoe and provided at its tip with a needle threading device or whirl for laying the thread in the hook of the needle.

One object of the invention is to provide a lockstitch sewing machine of the McKay type which may be operated smoothly at high speeds while feeding the work, and manipulating the needle and locking threads so as to produce a satisfactory seam having the stitches spaced evenly and formed in a predetermined uniform manner. Other objects of the invention are to provide in a lockstitch sewing machine of the McKay type, constructions and arrangements of parts capable of high speed operation, as above indicated, which will be strong and durable and in which all of the principal stitch-forming devices can be brought to rest in the desired positions quickly and accurately without injurious shock or jar.

With the above and other objects in view, certain features of the present invention relate to the provision in a lockstitch McKay type shoe sewing machine of improved stitch-forming and working-feeding mechanisms which will contribute to the formation of each stitch in a more reliable manner than heretofore, and which will render feeding of the work free of the difficulties met in the use of prior McKay type machines, particularly when operated at high speeds.

In a lockstitch McKay type machine there is no room in the rotatable horn for an awl reciprocating bar or for its actuating mechanism so that when an awl is used in this type of machine it is necessary to mount the awl bar on the same side of the work as the needle. The additional space, however, required for such an awl bar so limits and restricts the space available for the other stitch-forming instrumentalities, including the shuttle or loop taker and the loop spreader that it is necessary to reduce their size and movements to an undesirable extent, even to the point of causing the machine to sew irregularly or otherwise adversely affecting the quality of the work. To avoid this difficulty, means are provided in the lockstitch machine embodying the present invention for moving both the needle and

awl back and forth together along the line of feed about an axis parallel to the work supporting surface of the horn. To this end the respective reciprocating bars are supported in carriers arranged to move together as a unit in the line of the seam. With the use of a needle carrier movable along the seam line, a movement of the carrier while the needle is raised from the work, according to a further feature of the invention, is employed to engage the needle loop with the loop spreader, thus reducing the movement required of the loop spreader while transferring each needle loop to the shuttle and rendering it possible to so position the needle that the open hook will face in a direction most advantageous for transferring the loop. Another advantage of this arrangement is that the needle may be moved in the direction of feed while the awl is feeding the work, thus keeping the awl and needle from accidental engagement during vertical movements of both.

A still further feature of the invention, according to which effective operation may best be obtained when a work piercing awl arranged in the manner just outlined is employed, but which is capable of use to advantage with McKay type shoe sewing machines having other forms of construction, comprises means acting separately from the rotary loop taking movements of the shuttle to pull off from the supply of locking thread a measured amount for each stitch. According to the illustrated form of this feature, the pull-off means consists of a finger connected with the awl reciprocating bar and arranged with relation to the locking thread supply case to deflect the locking thread between the supply and the work. In connection with this feature, the shuttle in which the thread case is mounted is located directly behind the needle and awl so that the connections between the locking thread pull-off finger and the awl reciprocating bar may be made as short as possible.

Other features of the invention include novel and improved driving and stopping mechanism, a novel and improved needle threading whirl and whirl driving mechanism, a novel and improved needle thread loop retainer, and other novel combinations and arrangements of parts which are advantageous in use both with McKay and other types of sewing machines, as will be readily understood by those skilled in the art from the following description.

In the drawings illustrating the invention in its preferred form, Figure 1 is a view in right hand side elevation of a lockstitch McKay type

shoe sewing machine embodying the several features of the present invention; Figure 2 is a front elevation of the head of the machine illustrated in Figure 1; Figure 3 is a view in right hand side elevation, on a larger scale, of the head of the machine; Figure 4 is a view in front elevation on a somewhat larger scale of the head, the front cover having been removed; Figure 5 is a horizontal sectional detail view, taken along the line 5—5 of Figure 4; Figure 6 is a side sectional view of the front portion of the head on a further enlarged scale, taken along the line 6—6 of Figure 4; Figure 7 is a horizontal sectional detail view, taken along the line 7—7 of Figure 6; Figure 8 is a sectional plan view, taken along the line 8—8 of Figure 3; Figure 9 is a vertical sectional view on a somewhat enlarged scale of a portion of the head of the machine taken on line 9—9 of Figures 8 and 10; Figure 10 is a sectional view of the parts illustrated in Fig. 9, taken along the line 10—10 of Figure 9; Figure 11 is a view in front elevation on a still further enlarged scale of the rotary loop taker which is in the form of a shuttle, and its associated parts, as viewed along the line 11—11 of Figure 6; Figure 12 is a sectional detail view illustrating the relation of the loop retainer to the lower part of the shuttle, as viewed from the line 12—12 of Figure 11; Figure 13 is a sectional plan view, taken along the line 13—13 of Figure 11; Figure 14 is a view of the same parts, taken in section along the line 14—14 of Figure 11; Figure 15 is a detail view of the shuttle and bobbin arrangement, as viewed along the line 15—15 of Figure 11; Figure 16 is a sectional plan view of a portion of the thread case, taken along the line 16—16 of Figure 11, illustrating the thread guiding and locking means associated with the shuttle thread measuring devices; Figure 17 is a detail view of the lock for holding the shuttle in operative position, as seen in Figure 14, but with the lock released; Figure 18 is a partially sectional view with the frame broken away, as viewed from the line 18—18 of Figure 8, of the presser-foot actuating mechanism; Figure 19 is a view in section of the presser-foot clutch, taken along the line 19—19 of Figure 18; Figure 20 is a sectional view of the presser-foot clutch taken along the line 20—20 of Figure 19; Figure 21 is a sectional view of the presser-foot clutch, taken along the line 21—21 of Figure 19; Figure 22 is a detail view of a portion of the presser-foot unlocking and the loop retainer actuating mechanisms, as viewed from the front of the machine; Figure 23 is a view in left hand side elevation of the upper portion of the base of the machine in which the main driving and stopping controlling means is located; Figure 24 is a view in front elevation of the same portion of the base and also of the work supporting horn of the machine; Figure 25 is a view in right hand side elevation with the side cover removed, of the portion of the base containing the driving and stopping controlling means, as viewed along line 25—25 of Figure 24; Figure 26 is a detail view on an enlarged scale illustrating in section the needle thread tension of the machine; Figure 27 is a sectional plan view of a portion of the base, taken along the line 27—27 of Figure 25; Figure 28 is a front view of the same portion of the base, partly in section, taken along the line 28—28 of Figure 25, with the machine at rest; Figure 29 is a similar view with the machine in starting position, certain parts being broken away to show the underlying construction; Figure 30 is a view in side elevation of 75

the control connections extending between the head of the machine and the base for causing disconnection of the actuating devices from their respective operating shafts, illustrating the disconnectible elements in disconnected positions; Figure 31 is a view of the same connections illustrating the disconnectible elements in connecting positions; Figure 32 is a view in side elevation, and partly in section, of the rotary horn of the machine; Figure 33 is a sectional view of a part of the drive connections for the whirl in the horn, taken along the line 33—33 of Figure 32; Figure 34 is a sectional side view on an enlarged scale of the top of the horn showing the needle threading whirl, taken on the line 34—34 of Figure 35; Figure 35 is a plan view of the horn tip; and Figures 36 and 45 inclusive, are detail views illustrating the stitch forming and work feeding devices in successive operating positions assumed during a single stitch forming cycle of operation in the machine.

The sewing machine illustrated in the drawings is of the McKay type arranged with a straight hook needle, a rotatable shoe supporting horn and other stitch forming devices for sewing a locksmith seam. So far as the general manner of sewing is concerned, the machine is much the same as the machine illustrated in inventor's prior patent previously referred to, in which each stitch is formed by inter-locking a loop of needle thread with a locking thread during one cycle of stitch-forming operations, and in which the stitch thus formed is set during a succeeding cycle of operations.

The stitch forming and work feeding devices of the machine include in addition to the straight hook needle, indicated at 30, Figs. 2 and 4, a straight work penetrating and feeding awl 32 at the side of the work with the needle, a loop taker or shuttle 34, a loop spreader 36, a presser-foot 38, a two-armed take-up 40, 42, Figs. 1 and 24, a needle thread tension and lock 44, and a rotary needle looper or whirl 46, Figs. 1 and 34. The whirl 46 rotates in the usual way at the tip end 45 of the horn, indicated at 48, the horn being rotatable in a forwardly extending portion 50 of the main base 52 of the machine, and having a substantially flat work supporting surface. Rising from the rearward portion of the base 52 is a hollow supporting column at the upper end of which 50 is a sewing head frame or casing 54 overhanging the horn and having located therein most of the principal stitch forming devices.

In certain previous sewing machines, the work 55 is fed by an awl located at the same side of the work with the needle and arranged to penetrate substantially through the work and to move laterally therewith in the direction of feed into line with the needle, which has no lateral movement in the line of feed. The reciprocating movements of the needle and awl in these machines are required to be so timed that the downward movement of the needle is delayed to keep it out of the way of the awl until the awl reaches the uppermost portion of its stroke. The limitations enforced by this requirement restrict the reciprocating movements of the needle and awl to an undesirable extent, particularly when the machine is to be operated at high speeds.

In the present machine these objections are avoided by spacing the needle from the awl in the direction of the feed a distance of exactly a stitch length and then moving the needle and the awl laterally as a unit about an axis parallel to the work supporting surface of the horn, so

that the needle, after the return movement of these parts, will be directly over the awl hole or puncture in the work and will remain in the seam line at all times.

The specific construction of the parts is illustrated in Fig. 4, the needle 30 being mounted in the lower end of the reciprocating needle bar 56, slidingly mounted in the carrier 58 which is pivoted at its upper end to the stud 64 fixed in the top of the machine to permit a lateral swinging movement of the needle. The awl 32 is similarly secured to the lower end of the awl reciprocating bar 62, slidingly mounted in its carrier 60, which is also pivoted upon the stud 64 to permit lateral feeding movements of the awl.

Both the needle and awl carriers extend downwardly through a slot 63 in the bottom wall or partition 54 of the head of the machine, the slot being of sufficient length laterally to provide for swinging movements of the carriers.

The needle and awl carriers are secured together at their lower ends in fixed spaced relation so that when the awl carrier is oscillated about the pivot 64 to impart the feeding and return movement to the awl, corresponding oscillatory movements will be imparted to the needle carrier and the needle.

The specific form of connection between the awl and needle carriers is shown in Fig. 5 and comprises a plate 66 secured at one end to the awl carrier by means of the clamping bolt 68, and provided at the other end with a forwardly bent flange carrying the threaded abutment screw 70 against which the needle carrier 58 is firmly pressed by the compression spring 72 between the carriers. By adjustment of the abutment screw 70, the needle carrier may be brought to the proper distance from the awl carrier so that the needle will be in position to enter the hole or puncture in the work after the awl has been withdrawn and returned to work puncturing position.

In the machine illustrated in the drawings, the length of feed is fixed and can be altered only by the replacement of the feed cam with a differently shaped cam, the feeding movement being imparted to the awl carrier through a cam roll 74 rotatably mounted in a lug on the awl carrier, and engaging a suitably shaped cam slot in the front face of a cam disk 76 removably secured to the forward end of the main sewing shaft 77 by a set screw 78 (see Figs. 4 and 6).

The movements of the needle simultaneously with the awl not only avoid all possibility of interference between their parts, but the movement of the needle in the direction of the feed also serves, as will be hereinafter more fully described, to cause one side of each loop of thread carried by the threaded needle to be engaged by the loop spreader, so that the needle loop may be transferred to the shuttle by a single movement of the spreader away from the seam line.

For reciprocating the needle and awl towards and from the work, trains of cam actuated connections are provided including a pair of separate bell crank levers 78 and 80 oscillating on a fixed horizontal shaft 82 extending parallel to the line of the seam (see Figs. 4 and 6). The needle reciprocating lever 78, as shown in Fig. 4, is at the left side of the needle carrier 58, and the awl reciprocating lever 80 is at the right of the awl carrier 60 in order to transmit the motions of the levers as directly as possible to the needle and awl reciprocating bars respectively. The forward ends of the oscillating levers 78 and

80 are connected by means of links 84 and 86 to blocks 88 and 90 clamped to the central portions of the respective reciprocating bars, the blocks having projections sliding in vertical grooves in their respective carriers to prevent rotation of the bars (see Figs. 7 and 8). To oscillate the bell-crank levers 78 and 80, the lower arms of the levers are connected to disconnectible notched links 92 and 94 respectively, the notched rear ends of which are arranged to be held by springs 95 in engagement with the longitudinally extending pins in the upper ends of separate follower levers 96 and 98, respectively, actuated by grooves in a cam 99 on the sewing shaft 77 and fulcrumed on the side of the head frame at opposite sides of the shaft.

The loop spreader 36 consists of a downwardly extending curved arm having a hooked portion arranged with its point directed in the same direction as the beak of the shuttle while entering the needle loop. The loop spreader arm is secured at its upper end to the left end of a rock shaft 100 (see Figs. 3 and 4) mounted in a fixed bearing 102 disposed parallel to the seam line so that the spreader has a single oscillatory movement away from the seam line in spreading the loop. At the outer end of the shaft 100 (see also Fig. 3) is secured an actuating arm 104 connected to a horizontal, rearwardly extending link 106, the rearward end of which is connected to a crank 108 on arm 109 made fast to an oscillating shaft 110. The shaft 110 passes through bearings in the right side wall of the head frame or casing, as shown more clearly in Figs. 9 and 10. On the shaft 110 there is formed a series of pinion teeth 112 meshing with a gear segment 114 on the lower arm of a lever 116. The lever 116 is fulcrumed on a stud 118 carried by the left wall of the head frame and is driven from the cam 99 on the main sewing shaft 77 through connections including a notched link 120, the notched end of which engages a pin at the upper end of a cam actuated lever 122 mounted for oscillation upon a stud 124. To hold the notched end of the link 120 against the pin, a spring 125 is provided.

The loop of needle thread is brought directly over the loop spreader by a supplementary movement of the needle in the direction of the feed while it still holds the loop in its hook, thus bringing the loop spreader between the two legs of the loop at which time the crank 108 which actuates the spreader is in its extreme rearward position, as shown in Fig. 3, with the center line of the link 106 intersecting the axis of the shaft 110. The position of the loop spreader, therefore, as it enters the needle loop is definitely fixed, and slight variations in adjustment or looseness in the actuating mechanism will have little effect on the proper alignment of the loop spreader with the needle.

For drawing off a measured length of locking thread for use in each stitch, certain types of hook needle sewing machines are provided with means actuated either by the rotary movements of the shuttle or by a separate pull-off device. In a McKay type machine, the space is so crowded at the side of the work where the shuttle is located by the proximity of the needle bar and the work feeding mechanism that the addition of a device separate from the shuttle for pulling off locking thread from the supply is rendered difficult. In the machine hereinafter described, however, the shuttle is so located with relation to the other stitch forming devices that the reciprocating movements of the awl can be

employed to pull off a measured length of locking thread for use in each stitch.

Referring to Figs. 4 and 6, the feature of the invention relating to the locking thread pull-off device comprises a vertical thread deflecting rod or finger 126 on the awl bar 62 offset in a rearward direction and provided with an inverted V-shaped notch at its lower end. The upper end of the thread deflecting rod passes through a lug at the side of the clamp block 90 surrounding the awl reciprocating bar, and is adjustably secured in the block by means of a set screw 128 (see Figs. 7 and 8). The notched lower end of the deflecting rod is arranged to engage the thread between the locking thread supply in the bobbin or thread case and the work while the awl is completing its descending or puncturing stroke, being withdrawn from engagement with the thread when the awl rises so that the loop of needle thread in passing over the shuttle will not be caught by the deflecting rod (see Figs. 36 to 41). The length of locking thread thus measured is used up in the stitch formed by the previous loop of needle thread, which is pulled into the work when the last-formed needle loop is passing over the shuttle.

The shuttle or locking thread supply is contained within a hollow discoidal case 130 (see Figs. 11 to 17) rotatably mounted upon a central stud 132 extending forwardly from the rear wall of the shuttle concentric with the axis of shuttle rotation, the supply being in the form of a wound bobbin 134 rotatable upon a central tubular portion of the thread case 130. To keep the thread case from rotating with the shuttle, the forward face of the thread case is provided with a transverse rib 136 engaged along its under side by the horizontal portion of a positioning arm 138. The arm 138 extends downwardly from the head frame of the machine, being bent to clear the spreader bearing 102.

The locking thread is guided from the bobbin 134 through an opening 140 in the side wall of the thread case along a connecting groove in the side wall towards the front of the thread case and along the upper side of the rib 136. The rib 136 is suitably slotted to provide space for the entrance of the notched end of the locking thread measuring rod 126 and to receive a yieldingly actuated gripping jaw in the form of a pivoted dog 142 illustrated in Figs. 11 and 16, the measuring rod receiving slot and the slot for the dog 142 being separated by a thread guiding abutment 144 between which and the dog the thread passes. The thread is acted upon before it reaches the rib 136 by a tension spring 146 secured to the front wall of the thread case. The spring 146 is sufficiently heavy to prevent movement of the thread from the thread case while setting a stitch.

When the rod 126 deflects the thread, the dog 142 grips the thread against the abutment 144 to lock the thread and prevent its movement from the work. After the rod is raised, the needle loop, passing over the thread case, draws the measured length of locking thread past the gripper dog 142, the pivot 148 of the dog being so arranged that the gripping action of the dog is readily released except for the yielding force of a U-shaped spring 150 which holds the dog in operative position.

To afford convenient removal of the thread case when the bobbin 134 requires refilling, the shuttle, in the form of the invention illustrated, is arranged to be shifted laterally from its op-

erative position in the machine behind the needle and awl bars to a position exposing the thread case at the left side of the needle, as shown in dotted outline in Fig. 13.

5 To allow the shuttle to be shifted in this manner, the race for the beveled circumferential flange of the shuttle is formed in a race block 152, and this race block is rigidly secured to the forward end of a laterally movable carrier 154 10 in which is journaled the shuttle driving shaft 162. At its rear end the shaft 162 is connected by a flexible coupling as illustrated in Fig. 3, comprising driven and driving parts 164, 166 to a shaft 168 rotating in inclined bearings in the 15 lower part of the head frame. The carrier 154 is thus pivotally supported at its rear end by means of the shuttle driving shaft 162 and flexible coupling 164, 166 so as to permit a horizontal swinging movement of the carrier to expose 20 the thread case at the left of the needle bar. When the shuttle is in operative position the coupling 164, 166 is straightened, the shafts 162 and 168 then being in alignment. At its forward end, the carrier 154 is provided on its upper side 25 with a flat surface which, together with a flat surface on the upper side of the race block 152, bears against a flat guiding surface on the overhanging portion of the sewing head frame. To hold the carrier 154 and race block 152 against 30 this guiding surface, the race block is provided with a flange 155 (see Fig. 11), which projects over a tongue 156 extending from the side of the bearing 102 for the loop spreader shaft, when the shuttle race block is in operating position, 35 and the carrier 154 is provided with a groove (see Fig. 14) which is engaged by a supoprtng and guiding ribbed plate 158 on the head frame, which plate also supports the carrier when the carrier and shuttle race block are moved out of operating position. The movement out of operating position is limited by a stop pin 159 which stops the carrier and race block in the dot-and-dash line position indicated in Fig. 13.

The driver for the shuttle is in the usual form 45 of an arm 160 secured at the forward end of the shuttle drive shaft 162.

The carrier 154 is locked in operative position by means of a clamping cam 170 (Figs. 13 and 14) rotatable about a screw 172 threaded into the 50 forward end of the carrier and provided with a knurled head for manual rotation. When the shuttle is to be shifted, the clamping cam is rotated to the position shown in Fig. 17 so that a cutaway portion of the cam is brought into alignment with the lower end of a stud 174 against which the cam is wedged to lock the shuttle in 55 operative position. To hold the carrier 154 more securely in operative position, a plate 176 (Figs. 11 and 13) having a slotted portion to clear the 60 stud 174 is secured to the carrier by a screw 173 and is provided with a rib to enter a lateral recess in the head frame.

After drawing a loop of needle thread through 65 the work, the needle begins to descend while the loop is being transferred to the shuttle, and after the needle loop passes over the shuttle, the take-up acts to draw the loop partway towards the work as in the machine of inventor's patent. To shorten the time required to pass the needle loop over the shuttle, the shuttle is rotated twice during each stitch forming cycle of the present machine, the needle loop passing over the shuttle during the first rotation in each cycle. As in the machine of the patent, the needle loop is left re-

maining above the surface of the work until the next stitch forming cycle to provide thread as one side of the succeeding needle loop is being drawn through the work.

In order to prevent variation in the length of needle loop left remaining above the surface of the work after being drawn from the shuttle by the take-up, the shuttle race block 152 in the present machine is provided with a loop retaining hook finger 178 arranged to enter and hold each loop momentarily as the take-up reaches the end of its taking-up stroke. The loop retaining finger also holds the needle loop tight while the whirl 46 lays the thread in the needle barb, thus insuring a reliable looping operation. The finger 178 is formed at the lower end of an arm 180 mounted at its upper end on a pivot 182 and arranged to enter a slot (see Fig. 11) formed in a downwardly extending portion of the block 152. To release each needle loop from the loop retainer as the threaded needle passes through the work, the upper end of the retainer arm 180 is provided with a toothed portion engaging a notch in the lower end of a vertically sliding rod 184 passing through a passage in the block 152. The upper end of the passage in the block is enlarged to receive a spring 186 surrounding the rod 184 and the rod is provided with a head against which the spring 186 acts in a direction to maintain the loop retaining finger in an active position. The rod 184 is depressed to release each needle loop by means of a plunger 188 slidably supported in alignment with the head of the rod 184 within a bore in the lower wall of the head frame. The plunger 188 is provided with an off-set arm to which is secured a retracting pin 190 (Fig. 14) engaged at its lower end by a spring 192 supported in a second bore at the rear of, but parallel to the bore in which the plunger 188 is mounted. The plunger 188 is forced downwardly at the proper time in each cycle by means of an arm 194 (see Figs. 6 and 22) extending towards the left from a short shaft 196 rotating in a suitable fixed bearing and carrying at its rearward end a cam follower arm 198 actuated by the cam 99 on the sewing shaft. The arrangement of the plunger 188 and the loop retainer actuating rod 184 is such that the shuttle may be shifted from operative to inoperative positions while the machine is stopped, the rod 184 being moved out of alignment and disconnected from the plunger.

The presser-foot, as best shown at 38 in Fig. 4, is secured to the lower end of a vertical bar 200 slidably supported in the head frame of the machine and held yieldingly in lowered position by a relatively light spring 202 coiled about the upper end of the bar between a shoulder on the bar and an adjustable threaded sleeve 204 forming an upper bearing for the bar. The presser-foot is actuated in the usual way to release the work before each feeding movement of the awl takes place, and to hold the work in place both while the needle and awl are being retracted from the work and while each stitch is being set by the shuttle.

To avoid the use of heavy spring pressure on the presser-foot, as in previous machines, while permitting the machine to be operated at high speeds, the presser-foot is actuated positively in the present machine through cam actuated mechanism towards the work and just before the presser-foot reaches a work clamping position, the cam actuated mechanism is disconnected from the presser-foot so that the presser-foot

may take a position determined by the thickness of the work, the actuating spring not being required to move the presser-foot, but merely holding it in position when stopped by the work. A 5 spring of proper strength to move the presser-foot from raised position into engagement with the work with sufficient rapidity when the machine is operating at high speed, ordinarily would cause the presser-foot to strike the work with 10 such force as to produce undesirable indentations. By positively actuating the presser-foot in the manner outlined, a lighter actuating spring may be used so that indentation of the work from this cause is avoided.

15 The mechanism for actuating the presser-foot (see Figs. 4 and 18 to 21) comprises an oscillating clutch, the driven member of which is connected to the presser-foot bar 200 by means of a link 208 connected at its lower end to a stud 209 on a 20 block 206 secured to the presser-foot bar and connected at its upper end to an arm projecting from the driven member 210 of the clutch. The driven member 210 is in the form of a drum and is rotatably mounted on the horizontal shaft 82 at the forward part of the sewing head frame. The driving member 212 of the clutch is rotatably mounted on the shaft 82 at one side of the driven member 210 and extends within the overhanging rim of the driven member, as best shown in Fig. 20. To actuate the driving member 212, it is positively connected by interlocking projections and notches to the hub of an arm 214 also rotatably mounted on the shaft 82 and connected by a link 216 (see Fig. 18), to a cam actuated lever 218 mounted to oscillate on a stud 219 secured in the machine frame. Oscillation of the lever 218 oscillates the driving member of the clutch to impart upward and downward movements to the presser-foot bar, as hereinafter described, the extent of which movements can be varied by adjusting the pivotal connections 217 of the link 216 with the lever 218 along a curved slot in the lever.

45 Means are provided for locking the driven and driving members 210, 212 of the clutch together and for unlocking them during each stitch-forming cycle, the presser-foot bar being positively actuated in both directions so long as the clutch members are locked, and being free from the influence of the clutch as soon as the members are unlocked. The clutch members are locked during the greater part of each stitching cycle and are unlocked just before the presser-foot clamps the work.

55 The means for locking and unlocking the members 210, 212 of the clutch comprise a series of tapered rolls 220 located between the members, as best shown in Figs. 20 and 21, and fitting against a correspondingly tapered surface on the inner side of the overhanging rim of the driven member 210. The rolls are held in recesses in the periphery of the driving member 212, which recesses are provided with tapered surfaces extending axially in contact with the rolls and act to move the rolls bodily with the driving member in each direction as the driving member is oscillated. Alternate recesses in the driving clutch member have surfaces engaging the rolls which slope outwardly away from the axis of rotation in opposite directions, as clearly shown in Fig. 21, which cause certain of the rolls to lock the clutch members together when then the driving member is rotated in one direction and cause the other rolls to lock the

member together when the driving member is rotated in the other direction, the action of each set of rolls being similar to that of the well-known Horton clutch. The wedging surfaces of the clutch members are so disposed that the tapered rolls, when moved axially to the right, as viewed in Fig. 20, become wedged between the surfaces and lock the clutch members together so as to prevent relative movement in either direction. When the rolls are withdrawn axially from the tapered spaces between the clutch members, the clutch members are disconnected.

The tapered rolls 220 are held in an axially movable retaining cage 222 surrounding the shaft 82 between a collar portion of the cage and a plurality of curved fingers at the opposite end of the cage. To press the tapered rolls 220 equally into engagement with the clutch members, when the cage is moved axially, each roll is provided with a central recess within which is held a compression spring 224 supported by the collar portion of the retaining cage.

To disconnect the clutch members 210 and 212 at the proper time in each stitching cycle, so that the presser-foot may yieldingly engage the work, the cage 222 is actuated along the shaft 82 in a direction to withdraw the tapered rolls 220 from between the clutch members. To so actuate the cage, an unlocking bar 228 is mounted in a horizontal guideway of the head frame and is provided with a forked plate 226 fitting between a flange of the cage and a collar secured to the hub of the cage. Referring to Figs. 4, 6, 8 and 22, the lower surface of the unlocking bar 228 is formed with rack teeth, engaging a segment 230 connected to one end of a rock shaft 232 having at its other end an arm 234 provided with a cam roll 236. At the right end of the unlocking bar 228 is an axial bore arranged to receive a spring 238, the outer end of which engages a cover plate 240 secured to the side wall of the head frame. The spring 238 tends to force the bar 228 towards the left, causing the cam follower 236 to engage the outer surface of a cam 241 on the main sewing shaft.

The cam for actuating the presser foot lifting lever 218 is so cut that the presser-foot is raised to release the work as the beak of the shuttle enters the needle loop, as indicated in Fig. 39, thus permitting the needle thread extending through the needle opening in the horn to move more freely between the undersurface of the work and the tip of the horn as the needle loop passes over the shuttle. Just as the previous stitch is set, and while the work is still released, the presser-foot is lowered to hold the work lightly against the tip of the horn, after which the presser-foot clutch is unlocked to allow the position of the presser-foot to take a proper clamping position on the work.

The take-up mechanism is illustrated in Figures 24 and 25 and is of substantially the same construction and mode of operation as the take-up disclosed in inventor's U. S. Letters Patent No. 2,144,766 dated January 24, 1939, in which the two arms 40 and 42 are pivotally mounted one above the other to swing substantially in the same vertical plane. In taking up the thread, take-up rolls 242 at the outer ends of the take-up arms cooperate with a fixed perforated guide 243 and a roll 244 arranged so that the thread coming from the supply tension 44 passes first around the roll 244, and upwardly over the upper take-up roll, under the lower take-up roll, upwardly to the upper guide 243, and from this

guide through the horn to the whirl at the tip of the horn. The take-up arms are actuated through intermeshing pinions 246 secured to the inner ends of the shafts on which the arms are mounted, a bevel gear 248 connected to the lowermost pinion 246, a bevel gear segment 250 engaging the bevel gear 248, a lever 252 on one arm of which the segment 250 is formed and a notched link 254 pivotally connected to the other arm of the lever 252 and arranged to engage at its notched end a pin 256 carried by a cam actuated lever 258, the levers 252 being fulcrumed on a bolt 259 and the lever 258 on a bolt 260 secured in the side of the main base of the machine.

The thread tension comprises a pair of opposed discs between which the thread passes, supported on a central sliding rod 261 (see Figs. 25 and 26) loosely mounted in a passage through the front wall of the base. To provide a uniform tension in setting each stitch, there is the usual thread tensioning spring 262 surrounding the outer end of the rod between an adjusting nut 263 on the rod and the tension disks 44, forcing the disks together towards the front wall of the base 50. While the take-up is acting to draw each loop of needle thread from the shuttle, the resistance against moving the thread between the tension discs 44 is increased to the point of locking the thread, due to the presence of a pair of lock nuts 264 on the rod 261 within the coils of the spring 262 in such a position that when the rod 261 is pulled rearwardly the nuts act on the discs 44 to apply a greater pressure on the thread between the discs. To pull the rod 261 rearwardly, the rod carries a relatively heavy thread locking spring 265 within the enclosure of the main base 50, the spring 265 urging the rod rearwardly and being of sufficient strength to overcome the force of the spring 262. While each stitch is being set, the locking spring 265 is held inoperative and compressed through mechanism comprising a bell crank lever 266 to which the rod 261 is connected, fulcrumed on a stud bolt 267 and arranged with a horizontal slotted arm (see Figs. 27 and 29), a vertical link 268 sliding in the slot of the arm and having a head at its lower end to engage the slotted arm of lever 266 when the link 268 is raised, and a cam follower lever 269 oscillating on a stud 270 to which lever the link 268 is connected. The lever 269 is so actuated by a cam on the shaft 272 that the heavy spring 265 will become effective in locking the thread just after each needle loop is carried over the top of the shuttle.

The operation of the work penetrating and feeding awl, the shuttle thread deflecting rod 126, the presser-foot 38 and others of the stitch forming devices will be clearly understood from an inspection of Figures 36 to 45 inclusive. In Figure 36, the parts illustrated, with the exception of the presser-foot, are shown in positions assumed when the machine is stopped, the presser-foot ordinarily being raised on stopping the machine, but as illustrated, the presser-foot is in engagement with the work. The needle and awl are in their uppermost positions, the needle, having received a loop of needle thread, has moved in the direction of feed to engage the thread with the loop spreader 36. From this point, the loop spreader moves rearwardly to open up the loop of needle thread held by the needle, and the needle and awl are back fed while the awl descends towards the work to the position illustrated in Figure 37. During the con-

tinued downward movement of the awl, the work is completely penetrated and the deflecting rod 126 acts before the last formed needle loop passes over the shuttle to measure off a length of shuttle thread, as shown in Figure 38, for the stitch being formed by the next to last needle loop. Immediately after the locking thread is measured, the shuttle, during its first rotation of a cycle, enters the spread needle loop, as indicated in Figure 39. From the position of Figure 39, the presser-foot is raised to release the work, the awl moves in the direction of feed to bring the awl perforation into line with the needle opening at the tip of the horn, and the needle loop which, by this time is disengaged from the needle and spreader is being drawn rapidly by the shuttle from the horn, as indicated in Figure 40. Each stitch is set just before the positions of parts illustrated in Figure 41 are reached, the last-formed needle loop having passed the top of the shuttle, as shown in this figure, the presser-foot having again gripped the work, the awl having withdrawn and the locking thread having been drawn into the work by the next to last formed needle loop. Thereafter, the thread is locked between the tension discs 44, and the take-up causes the needle loop to be drawn from the shuttle. The needle then begins its downward movement towards the work, and is back fed into line with the awl perforation. While this is taking place, the receding needle loop is being caught by the loop retaining finger 178, as shown in Fig. 42. During the second rotation of the shuttle in a cycle while the needle loop is held by the loop retaining finger 178, the needle enters the awl perforation and the whirl lays the thread in the needle, the position of the parts while the needle is in the work being illustrated in Figure 43. As soon as the threaded needle begins to rise, the loop retaining finger releases the needle loop so that the loop may be drawn still further towards the work as the new loop of thread is being drawn through the work by the needle. The relation of the new and previous loops, as the needle rises, is illustrated in Fig. 44. After the needle reaches its uppermost position, as indicated in Fig. 45, it again moves in the direction of feed towards the loop spreader to the position of Fig. 36, and the next to last loop of needle thread surrounding the locking thread is drawn farther towards the upper surface of the work ready to be pulled in during the succeeding stitching cycle while the last formed needle loop passes over the shuttle.

Due to the location of the takeup, as in the McKay type sewing machine of inventor's Patent No. 1,885,927, at a distance from the main sewing shaft and close to the base of the work supporting horn, a horizontal continuously rotating secondary drive shaft indicated in Fig. 1 at 272 is provided in the present machine, geared to rotate at the same speed as the main sewing shaft 11 and the oscillating train of mechanism between the secondary shaft 272 and the take-up is made as short as possible to reduce vibration at high speeds. Between the main sewing shaft in the sewing head and the secondary shaft in the base, there is a vertical shaft as in the machine of Patent No. 1,885,927, indicated at 273, and the vertical shaft is provided with bevel gears, as at 274, meshing with similar gears on the main sewing and secondary shafts, respectively. In the present machine there are also driving connections from the vertical shaft 273 to the shuttle drive shaft 162. The secondary shaft 272 also

carries a cam 275 as a convenient means for actuating the thread lock operating lever 269 in the base.

When the machine of inventor's prior Patent No. 1,885,927 is stopped, the train of connections comprising the mechanism for actuating the needle is disconnected from the main sewing shaft by the operation of driving and stopping means so that the needle may be brought to rest at a predetermined time in each cycle of operations without simultaneously stopping the sewing shaft. Others of the stitch forming devices in that machine are driven from the needle actuating train of mechanism and are therefore disconnected with the needle. The main take-up, however, being actuated by a separate train of mechanism in the base of the machine close to the rotary horn, is not brought to rest, but continues its taking up and giving up movements as the main sewing shaft continues to rotate after the needle is disconnected. If the main sewing shaft comes to rest at the end of the giving up stroke of the take-up the operator in removing the sewed shoe from the horn may draw through the horn the amount of thread given up by the take-up. This may cause a considerable length of thread to be wasted, and in case the thread is cut close to the horn, the take-up in its initial movement, as the machine is started, may pull the end of thread from the tip of the horn so that the machine will require rethreading.

In the illustrated machine, the driving and stopping means, when actuated, disconnects from the sewing shaft 11 the take-up in the base of the machine, as well as certain of the stitch forming devices in the sewing head during the continued rotation of the main sewing shaft. The needle is disconnected when disengaged from the work and the take-up is disconnected from its driving mechanism near the end of its take-up stroke, but at a position sufficiently spaced from the end of its stroke to provide a short length of thread between the shoe and the end of the horn when the shoe is lifted from the horn, so that the desired length of thread will extend from the needle receiving opening in the horn when the thread is severed close to the shoe. In this way only the amount of thread required to start a new seam will be withdrawn from the horn, and there will be no excessive waste. When starting the machine the take-up is again connected to the sewing shaft, but at that part of a cycle in which the take-up is giving up thread, so that the end of thread will not be pulled from the whirl in the horn.

The driving and stopping means in the present machine acts substantially in the same manner as in the outsole shoe sewing machine of inventor's prior U. S. Letters Patent No. 2,144,766, in which disconnection of the stitch forming devices is caused by the operation of a single controller, but in the case of the present machine the controller operates through connections extending from the sewing head to the main base 52 where the take-up is located. The trains of mechanism between the main sewing shaft and the needle, awl, loop spreader, and take-up together with the respective disconnectible notched links controlled by said connections have already been described.

The control connections for the disconnectible notched links of the actuating mechanisms are best shown in Figs. 30 and 31, in which the disconnected and connected positions thereof are respectively illustrated, the disconnectible

notched links for the loop spreader and the take-up only being illustrated in these figures. The other connections to the notched actuating links for the awl and needle which comprise a part of the control connections are shown most clearly in Figures 6 and 8. These last mentioned connections, however, act in the same manner as those for the loop spreader, so that a description of the connections illustrated in Figures 30 and 31 will apply equally well to the awl and needle control connections, like reference numerals being used in each instance. From each disconnectible notched link in the sewing head of the machine there projects a stud 277 sliding in a slot in the horizontal arm of a bell crank 278 fulcrumed on a bolt 279. The bolts 279 are mounted on an intermediate frame portion 280 in the main sewing head, the slotted bell crank 278 for disconnecting the notched link 94 of the awl mechanism being at the right side of the frame portion 280, and the needle and loop spreader disconnecting slotted bell cranks, both being at the left side of the frame portion 280. The bell cranks 278 at the left side of the machine are connected together by a single link 281, the rearward end of which is connected to a lever 282, secured to a horizontal shaft 283 fulcrumed loosely in the intermediate frame portion 280 of the head 54. The bell crank 278 for disconnecting the awl is actuated by means of a link 284 (Fig. 8) pivotally connected at its rearward end to an arm 285 also secured to the shaft 283 on which the lever 282 is mounted. Also cooperating with the pin 277 on each notched link when in raised position is a slotted plate 287 secured on the intermediate frame portion 280 in proper relation to the link so that the pins 277 for the respective actuated devices will enter the slots of plates 287 and be held in fixed positions when the machine stops. To actuate the take-up disconnectible link, the horizontal arm of the lever 282 is pivotally connected with the upper end of an elongated vertical link 288, the lower end of which is connected to a bell crank lever 289 fulcrumed on a stud 290 in the base 52. On the lowermost arm of the lever 289 is a gear segment 292, meshing with a similar segment 294 formed on a vertical arm of a three-armed lever 296. The lever 296 is rotatably mounted on a bolt 298 secured to the side wall of the main base and a horizontally extending arm of the lever is provided with a curved slot within which a pin 300 at the notched end of the link 254 projects. When the stitch-forming devices in the head of the machine are moved to disconnected positions, the notched link 254 of the take-up actuating mechanism is also moved to disconnected position. To maintain the take-up in the position in which it is disconnected while the main sewing shaft 77 and the secondary shaft 272 continue to rotate, the pin 300 on the notched link 254 is arranged to cooperate with an open ended slot in a vertical plate 302 (see Fig. 25) secured to a portion of the machine base.

The operation of the needle, awl, loop spreader and take-up is so timed that all of the devices will be at their proper stopping positions at one particular point in the revolution of the main and secondary shafts. At this point, the control connections cause the disconnectible notched links to be moved to disconnecting positions, the respective cam actuated levers being held stationary for a brief interval, due to the configuration of the cooperating cam grooves. Upon starting the machine, the control connections

cause the respective notched links to be moved into engagement with the projecting pins on the cam actuated levers at the same point in the revolution of the main and secondary shafts 5 while the pins on the cam levers are held in alignment with the notched portions of the disconnectible links.

The controller mechanism for actuating the control connections upon stopping and starting the machine is illustrated in Figs. 27 to 31, and is similar to that in the machine of Patent No. 2,144,766. To one horizontal arm of the three-armed lever 296 is connected a link 303 also connected to one arm of a lever 304 rotatably mounted on a short shaft 306 extending between a pair of inwardly projecting lugs carried by a cover plate 308 in the side of the main base. To oscillate the lever 304 about the shaft 306, the lever 304 is connected by a link 310 to an arm 10 of a stopping and starting controller lever 312 rotatable about a horizontal shaft 314 mounted on inwardly projecting lugs carried by the cover plate 308. When the stopping and starting lever is in stopping position, the toggle joint consisting of the link 310 and the downwardly extending arm of the lever 312 becomes straightened and locks the control connections. Upon reverse movement of the stopping and starting lever, the toggle joint formed by the link 310 and the arm 15 of the stopping and starting lever is broken, and a relatively heavy spring 316 stretched between the lever 304 and the cover plate 308 causes the control connections to be actuated and held in running positions as indicated in Figure 31. The movements of the stopping and starting control lever in both directions are limited by adjustable stop screws 318 in the cover plate 308 arranged to engage lugs formed on the stopping and starting lever above and below its shaft 314.

For shifting the controller lever 312 from one position to the other in stopping or starting the machine, the end of one arm of the lever is provided with a stopping cam roll 320 and the end of another arm of the lever is provided with the starting cam roll 322. The cam rolls 320 and 322 are arranged to cooperate with stopping and starting cams 324 and 326, respectively, carried by a cam disk 328. The cam disk 328 is mounted to rotate with the secondary drive shaft 272, but is movable longitudinally of the shaft to bring either the stopping or starting cam into operative position with relation to the cam rolls on the stopping and starting lever.

To move the cam disk longitudinally of the secondary shaft 272, the disk is connected to the stopping and starting foot actuated treadle of the machine. A circular groove 330, Figs. 24 and 27, is formed at the forward end of the cam disk and a pair of segmental blocks 332 are disposed in the groove 330 and pivotally supported at the lower ends of the arms of a yoke 334 secured to the inner end of a horizontal shaft 336. The shaft 336 passes loosely through the left side of the main base and at its outer end has secured to it a cross bar 338, one end of which is forked and provided with oppositely disposed stop screws 340 cooperating with a fixed lug 342 on the main base to limit the movement of the cross bar. The lower end of the cross bar is provided with a pivotally mounted perforated block 344 loosely surrounding one end of a horizontal treadle actuated rod 346. At either side of the block 344 surrounding the rod 346 there are coiled springs 348 acting alternately when the rod is actuated rearwardly and forwardly to rock the cross bar 70

yieldingly with its supporting shaft 336 in the desired direction, the springs 348 being held in proper positions on the rod by suitable collars 350 and 352, respectively, fixed to the rod. Between the ends of the rod 346 (see Fig. 23) is secured a block 354 pivotally mounted on one arm of a lever 356 having a fulcrum screw 358 in a cover plate 360 at the left side of the machine base. On the other arm of the lever 356 is pivotally mounted a block 362 to which the upper end of a vertical treadle actuated rod 364 is connected, the rod 364 being connected at its lower end to the foot treadle indicated at 366 in Fig. 1. For holding the treadle raised, the treadle rod 364 is surrounded by a spring 368 compressed between a lug on the machine frame and a collar secured to the rod. When the treadle is depressed, the horizontal rod 346 is actuated forwardly to cause the starting cam to be moved to operative position and when the treadle is released, the rod 346 is actuated rearwardly to cause the stopping cam to be moved to operative position.

Continued depression of the treadle after the starting cam has been moved along the secondary shaft 272 is utilized to connect the secondary shaft to its driving means, and upward movement of the treadle rod before the stopping cam is shifted to stopping position is utilized to disconnect the secondary shaft from its driving means, the springs 348 permitting continued movement of the rod 346 in either direction after the starting and stopping cam is moved along the secondary shaft. At the rearward end of the secondary shaft is mounted a loose driving pulley 370 which is constantly rotated by a belt passing under a pulley driven by a motor 371, illustrated in Fig. 1. The pulley 370 has an inner clutch surface arranged to be engaged by a clutch member 372 (see Fig. 23) rotatable with, but slidably along, the end of the second shaft 272. Connected with the clutch member 372 is a ring 374 mounted by means of diametrically arranged pins 376 to the upstanding arms of a yoke 378 secured to one end of a rock shaft 380 rotatable in a bracket 382 on the machine frame. At the left end of the rock shaft 380 is an upstanding arm 384 having a perforated block 386 pivotally mounted at its upper end and slidably mounted on the horizontal rod 346. To actuate the clutch when the rod 346 is moved, the rod has secured to it on either side of the block 386 a pair of collars 387 which provide a lost motion connection between the rod and the block 386.

Upon stopping the machine the presser-foot is lifted from the work and retained in this position until the machine is again started. To this end the control connections including the slotted lever 278, best shown in Figs. 6 and 8, for controlling the train of awl actuating mechanism is connected by means of a short link 384 to a horizontally slidable hooked rod 386. The rod 386 is supported in a guideway 388 secured to the intermediate frame portion 280 in the head of the machine and the hooked end of the rod embraces a pin 390 projecting from one side of the outer rotary clutch member 210 which is directly connected to the presser foot. Rearward movement of the rod 386 causes the clutch to be unlocked and clutch member 210 to be rotated in a direction to raise the presser foot. To unlock the presser foot before the clutch member is rotated, the rod 386 is provided with a cam surface arranged to engage a roll 392 mounted on the presser foot unlocking bar 228.

To avoid the possibility that the secondary shaft 272 will come to rest with the needle thread locked so that difficulty will be encountered in drawing thread from the supply when the sewed shoe is lifted from the horn, the control connections illustrated in Figures 30 and 31 are arranged to hold the needle thread lock released regardless of the position in which the secondary shaft stops. The three-armed lever 296 of the control connections is provided with a downwardly extending lug through which is threaded a set screw 394 adapted to engage an upstanding arm on the lock actuating bell crank lever 266. When the machine is running, the lever 266 and the tension disc supporting rod 261 are in the positions indicated in Figure 31 in which the lever 266 is free to be oscillated by the cam actuated lever 269. When the machine is stopped, the control connections move to the positions of Figure 30 in which the set screw 394 causes the lever 266 for actuating the thread lock to be held positively in lock releasing position.

The needle threading whirl or looper 46 herein-after described is of greater vertical thickness, but of smaller outside diameter than in the machine of inventor's patent, above referred to, and is so constructed that the upper part of the whirl projects laterally beyond the edges of the lower portion to provide a circular surface by means of which the upper end of the whirl may be rotatably supported in the horn. The whirl indicated in Figs. 34 and 35, is driven in the usual way by the engagement of a driving pinion 396 with bevel teeth 398 formed on the lower portion of the whirl, the teeth being inclined upwardly and towards the center of the whirl. The arrangement of the upper portion of the whirl is such that the thread is directed nearer to the work supporting surface of the horn than with the whirl of the machine of Patent No. 1,885,927, and extends between the work and the whirl more nearly at right angles to the needle, thus insuring that the needle will be looped in a more reliable manner than in the machine of the said patent. With this arrangement, the perforated tip cap covering the whirl is made thinner, the total thickness of the horn tip remaining the same.

In order to form the gear teeth 398 with full depth throughout their length, the whirl of the present machine is constructed of two button shaped parts 400 and 402 secured together by means of vertical rivets 404. The teeth 398 on the lower part 402 are cut before the two parts are assembled so that the shaping tool for the teeth may be carried the full length of the teeth, giving a full depth cut without interfering with the upper part of the whirl. The upper part 400 is formed with a shoulder projecting beyond the lower part 402 to cover the upper ends of the bevel teeth 398. For receiving the thread and the hooked end of the needle, the two parts 400 and 402 are formed with identical thread eyes and needle receiving openings, the ends of which are brought into registration when the parts are assembled. The lower part 402 is also formed in the usual way with a reduced portion beneath the gear teeth 398 for providing support within a lower bearing 406 in the horn, but due to the support provided about the circular surface of the upper button, the reduced portion is of much smaller size than in the usual construction.

The driving connections between the pinion 396 and the horizontal secondary drive shaft 272 include angularly disposed interconnected shafts

408 and 410 (Figs. 1 and 32), the upper one 408 supporting the pinion 396 at its upper end and the lower one 410 carrying a bevel gear 412 at its lower end. The bevel gear 412 meshes with a gear 414 driven from the secondary shaft 272 through gears 416 and 418.

In the machine of inventor's Patent No. 1,895,927, the gears corresponding to those indicated at 414 and 416 in the present drawings are mounted on a single shaft rotatable in bearings at either end, the upper one of which is supported in the lower flanged part of the horn frame, corresponding to the part of the horn frame indicated at 420, and the lower one of which is supported in a flanged horn supporting spindle corresponding to the spindle indicated at 422. When assembling the parts of the machine after manufacture, due to slight inaccuracies of construction, it is necessary to accurately line up the horn and the needle so that the needle will enter the needle receiving opening at the tip of the horn with accuracy. To do this, the flanged base of the horn is secured to the flange of the rotary spindle by means of bolts, similar to the one shown at 424, passing loosely through enlarged holes in the flanged base. When the bolts corresponding to the bolts 424 are loosened the horn may be moved a sufficient distance laterally on the spindle to locate the needle opening in the proper position, but the shaft connecting the gears corresponding to the gears 414 and 416 may become so tilted as a result that the driving relation between gears corresponding to the gears 412 and 414 is thrown out of proper mesh.

To prevent improper mesh between the whirl driving gears 412 and 414 of the illustrated machine, while adjusting the horn, the gears 414 and 416 are secured to separately mounted shafts 426 and 428, respectively. The upper shaft 426 rotates in bearings 430 supported in the base of the horn, and the shaft 428 is mounted in bearings 432 supported in the spindle 422. Between the adjacent ends of the shafts there is a flexible coupling comprising discs 434 having vertical lugs secured to the ends of the respective shafts and an intermediate disk 436 slotted to receive the lugs of the disks 434 is positioned between the disks 434. With the use of the flexible coupling, the horn 48 may be moved relatively to the spindle 422 to any desired relation without relative movement taking place between the driving gears 412 and 414.

The means for oiling the machine comprises a suitable pump 438 (see Fig. 1) located in the main base of the machine with its intake below the level of a supply of oil contained within the base. The pump 438 is operated through a vertical shaft 440 having at its upper end a bevel gear 442 meshing with a gear 274 on the secondary sewing shaft 272. When the pump is operated, oil is supplied to the parts in the base, and in the sewing head of the machine, in the form of spray through upstanding pipes 444 and 446. The pipe 446 in the head is perforated to supply oil to the cams and cam levers on the main sewing shaft 77, and also at its forward end to throw spray on the needle and awl reciprocating bars. Some of the oil directed at the needle and awl bars is thrown against a front cover 447 of the casing surrounding the sewing head. As the oil runs down this cover, unless otherwise prevented, it will run onto the work through the open

slot 63 provided for the needle and awl bar carriers.

To keep the oil in the sewing head casing from contact with the work, the forward wall 5 of the casing cover 447 in the sewing head is provided with a curved baffle plate 448, as shown in Figure 6. The baffle plate is bent rearwardly at its lower end and disposed at a higher level than the bottom wall of the casing surrounding 10 the slot 63. Beneath the bent lower edge of the baffle plate 448 is positioned the upwardly bent edges of a pair of aprons 450 and 452 (see Fig. 5) secured in surrounding relation, respectively, to the needle and awl bar carriers so as to close the 15 slot 63. The aprons 450 and 452 are arranged to overlap along their adjacent edges so that spacing adjustments between the needle and awl bar carriers may be readily made. To keep the 20 aprons in alignment, the aprons are slotted to receive the rod portion of the finger 126 which passes through them. The portions of the 25 aprons 450 and 452 surrounding the carriers are bent upwardly in close proximity to the carriers so that the oil running from the carriers will be 30 directed away from the slot through which the carriers project. The oil from the sewing head is carried rearwardly to the supporting column and into the base. To prevent the oil from running through the bearings for the shuttle drive 35 shaft 168, the bearings are surrounded by a sleeve 466 (see Fig. 3) mounted within the sewing head at a suitably inclined angle to drain rearwardly through the column into the base 52.

The presser foot mechanism herein disclosed 35 forms the subject-matter of a divisional application filed September 29, 1941, Serial No. 412,748.

The nature and scope of the present invention having been indicated, and a machine embodying the several features of the invention having been specifically described, what is claimed is:

1. A lockstitch sewing machine having, in combination, stitch forming devices including a straight hook needle, a work piercing awl, and a loop taker at the side of the work with the needle and awl, a work supporting horn, a presser foot, and means for moving the needle and awl back and forth together along the line of the seam about an axis substantially parallel to the work supporting surface of the horn.

2. A lockstitch sewing machine having, in combination, stitch forming devices including a straight hook needle, a work piercing awl, and a loop taker at the side of the work with the needle and awl, needle and awl reciprocating bars, a work supporting horn, a presser foot, and carrier means pivoted about an axis substantially parallel to the work supporting surface of the horn on which the needle and awl bars are supported and with which they are arranged to move together along the line of the seam.

3. A lockstitch sewing machine having, in combination, stitch forming devices including a straight hook needle, a work piercing awl, and a loop taker at the side of the work with the needle and awl, needle and awl reciprocating bars, a work supporting horn, a presser foot, carriers pivoted about an axis substantially parallel to the work supporting surface of the horn on which the needle and awl bars are supported and with which the needle and awl bars are movable along the line of the seam, and connections between the carriers for causing the carriers to move together as a unit.

4. A lockstitch sewing machine having, in

combination, stitch forming devices including a straight hook needle, a work piercing awl, and a loop taker at the side of the work with the needle and awl, a work supporting horn, a presser foot, means for moving the needle and awl together about an axis substantially parallel to the work supporting surface of the horn along the line of the seam, and means for adjusting the spacing of the needle and awl in the direction of feed.

5. A lockstitch sewing machine having, in combination, stitch forming devices including a hook needle, a loop taker, and a loop spreader, a needle reciprocating bar, a work supporting horn, a presser foot, and a carrier on which the needle bar is movable along the line of the seam to engage the loop of thread held by the needle with the loop spreader.

6. A lockstitch sewing machine having, in combination, stitch forming devices including a hook needle, a loop taker and a loop spreader, a needle reciprocating bar, a work supporting horn, a presser foot, and mechanism for actuating the needle bar in the direction of feed to engage the loop of thread held by the needle with the loop spreader.

7. A lockstitch sewing machine having, in combination, stitch forming devices including a hook needle, the open hook of which faces along the line of the seam, a loop taker, and a loop spreader acting to draw a side of each loop of thread held by the needle away from the seam line as the needle loop is being transferred to the loop taker, and means for actuating the needle along the seam line to engage the needle loop with the loop spreader.

8. A lockstitch sewing machine having, in combination, a main sewing shaft, stitch forming devices driven from the sewing shaft including a hook needle, a loop taker and a loop spreader for engaging one side of each loop of needle thread when brought into alignment with the needle, and spreader actuating mechanism comprising a rotary shaft, a crank on said shaft, and connections from the spreader to the crank including a link mounted on the crank arranged to move the spreader into alignment with the needle when the center line of the link intersects the axis of the rotary shaft.

9. A lockstitch sewing machine having, in combination, stitch forming devices including a straight hook needle, a work piercing awl, a loop taker and a loop spreader, needle and awl reciprocating bars, a work supporting horn, a presser foot, carrier means on which the needle and awl bars are supported and arranged to move together along the line of the seam, and mechanism for actuating the carrier means after the awl penetrates the work to feed the work and after the awl withdraws from the work to engage with the loop spreader the loop of thread held by the needle.

10. A lockstitch sewing machine having, in combination, stitch forming devices including a straight hook needle, a work piercing awl, a loop taker and a loop spreader, needle and awl reciprocating bars, a work supporting horn, a presser foot, carrier means on which the needle and awl bars are supported and arranged to move together along the line of the seam, and mechanism for actuating the carrier means in the direction of feed after the awl penetrates the work to feed the work and again in the direction of feed after the awl withdraws from the work to

engage with the loop spreader the loop of thread held by the needle.

11. A lockstitch sewing machine having, in combination, stitch forming devices including a straight hook needle, a work piercing awl, and a loop taker at the side of the work with the needle and awl, needle and awl reciprocating bars, a work supporting horn, a presser foot, carriers on which the needle and awl bars are supported and movable along the line of the seam, resilient means between the carriers, and adjustable means for holding the carriers relatively to each other against the force of the resilient means to cause the carriers to be moved together along the seam line in the direction of feed.

12. A lockstitch sewing machine having, in combination, stitch forming devices including a straight hook needle, a work piercing awl, and a loop taker at the side of the work with the needle and awl, needle and awl reciprocating bars, a work supporting horn, a presser foot, carriers pivoted to swing about an axis substantially parallel to the work supporting surface of the horn on which the needle and awl bars are supported and movable along the line of the seam, connections between the carriers for causing the carriers to move together along the seam line as a unit, and means for adjusting the spacing in the direction of feed between the carriers.

13. A lockstitch sewing machine having, in combination, stitch forming devices including a straight hook needle, a work piercing awl, and a loop taker at the side of the work with the needle and awl, needle and awl reciprocating bars, a work supporting horn, a presser foot, carriers on which the needle and awl bars are supported and movable along the line of the seam, and a single pivot about which said carriers swing when moved along the seam line.

14. A lockstitch sewing machine having, in combination, stitch forming devices including a straight hook needle, a work piercing awl, and a loop taker at the side of the work with the needle and awl, needle and awl reciprocating bars, a work supporting horn, a presser foot, carrier means on which the needle and awl bars are supported and arranged to move together along the line of the seam, and mechanism for reciprocating the needle and awl towards and from the work including a separate oscillating lever at either side of the carrier means, and a shaft on which the levers oscillate extending substantially parallel to the seam line.

15. A lockstitch sewing machine having, in combination, stitch forming devices including a straight hook needle, a work piercing awl, a rotary loop taker at the side of the work with the needle and awl, and a locking thread supply case about which the loop taker passes each loop of needle thread, needle and awl reciprocating bars, a rotatable shoe supporting horn, a presser foot, and means acting independently of the rotary movement of the loop taker for drawing off from the thread case a length of locking thread for each stitch.

16. A lockstitch sewing machine having, in combination, stitch forming devices including a straight hook needle, a work piercing awl, a rotary loop taker at the side of the work with the needle and awl, and a locking thread supply case about which the loop taker passes each loop of needle thread, needle and awl reciprocating bars, a rotatable shoe supporting horn, a presser foot, and means actuated by the awl bar while the awl engages the work for drawing off from

the thread case a length of locking thread for each stitch.

17. A lockstitch sewing machine having, in combination, stitch forming devices including a straight hook needle, a work piercing awl, a rotary loop taker at the side of the work with the needle and awl, and a locking thread supply case about which the loop taker passes each loop of needle thread, needle and awl reciprocating bars, a rotatable shoe supporting horn, a presser foot, means for drawing off from the supply in the thread case a length of locking thread for each stitch, and means on the thread case for preventing the locking thread from being pulled from the work while being drawn from the supply.

18. A lockstitch sewing machine having, in combination, stitch forming devices including a straight hook needle, a work piercing awl, a rotary loop taker at the side of the work with the needle and awl, and a locking thread supply case about which the loop taker passes each loop of needle thread, needle and awl reciprocating bars, a rotatable shoe supporting horn, a presser foot, means for drawing off from the supply in the thread case a length of locking thread for each stitch, and a yieldingly actuated gripper on the thread case arranged to prevent movement of the thread from the work while being drawn from the supply and to provide a tension for the locking thread while being drawn towards the work by each needle loop.

19. A lockstitch sewing machine having, in combination, stitch forming devices including a straight hook needle, a rotary shuttle at the side of the work with the needle, and a locking thread case within the shuttle, a shuttle race, a reciprocating needle bar, a work supporting horn, a presser-foot, and supporting means for the shuttle race comprising a carrier and a guideway along which the carrier may be shifted to carry the shuttle from an operative position in the machine behind the needle bar to a position exposing the thread case at one side of the needle bar.

20. A lockstitch sewing machine having, in combination, stitch forming devices including a straight hook needle, a rotary shuttle at the side of the work with the needle, and a locking thread case within the shuttle, a shuttle race, a reciprocating needle bar, a work supporting horn, a presser-foot, supporting means for the shuttle race comprising a carrier movable in the direction of feed and a shuttle drive shaft having a flexible coupling about which the shuttle race moves as a center when the position of the carrier is shifted.

21. A lockstitch sewing machine having, in combination, stitch forming devices including a straight hook needle, a rotary shuttle at the side of the work with the needle, and a locking thread case within the shuttle, a shuttle race, a reciprocating needle bar, a work supporting horn, a presser-foot, a shuttle drive shaft having a flexible coupling and supporting means for the shuttle race and drive shaft comprising a carrier, a guideway extending in the direction of feed, and means for locking the carrier in operative position on the guideway with the flexible coupling substantially in straightened condition.

22. A lockstitch sewing machine having, in combination, stitch forming devices including a straight hook needle, a rotary shuttle and a discoidal locking thread supply case within the shuttle having a rib projecting from one end sur-

face, a shuttle race, supporting means for the shuttle race comprising a carrier and a guideway along which the shuttle carrier may be shifted towards and from operative position in the machine, and an arm extending in the direction of the guideway for cooperating with the rib on the thread case when the shuttle carrier is in operative position to hold the thread case from rotation within the shuttle.

10 23. A lockstitch sewing machine having, in combination, stitch forming devices including a straight hook needle, a rotary shuttle and a discoidal locking thread supply case within the shuttle having a rib projecting from one end surface, 15 an arm cooperating with one side of the rib to hold the thread case from rotation within the shuttle, thread guiding means for directing the locking thread along the other side of the rib and thread deflecting means acting across the 20 path of the locking thread along the rib to draw off from the supply in the thread case an amount for each stitch.

24. A lockstitch sewing machine having, in combination with other stitch forming devices, 25 a hook needle, a loop taker, means for imparting to said loop taker a plurality of rotations during each stitch forming cycle, a locking thread supply case about which the loop taker passes each loop of needle thread during one of 30 said rotations, and means acting during said rotation after a needle loop has passed over the loop taker and before the stitch being formed by said needle loop is set to draw off from the supply in the thread case a length of locking 35 thread.

25. A lockstitch sewing machine having, in combination with other stitch forming devices, a hook needle, a locking thread supply case, a loop taker for passing each loop of needle thread 40 about the thread case and for setting the stitch formed by the loop of needle thread previously engaged by the loop taker, a take-up arranged to draw each needle loop from the loop taker, and means acting after the take-up reaches the 45 end of its loop drawing stroke and before the stitch being formed by the previous needle loop is set to draw off a length of locking thread from the supply in the thread case for use in completing said stitch.

50 26. A lockstitch sewing machine having, in combination with other stitch forming devices, a hook needle for drawing a loop of needle thread through the work and for simultaneously pulling the preceding loop of needle thread still further towards the surface of the work, a take-up 55 for drawing each loop of needle thread partway towards the work before the succeeding needle loop is formed, a loop taker arranged when engaging each needle loop to pull the preceding needle loop into the work and to set the stitch, and means acting after the take-up has reached the end of its thread drawing stroke and before the last-formed needle loop engages the loop taker to draw off from the supply in the thread 60 case a length of locking thread for use in completing the stitch formed by the preceding needle loop.

70 27. A lockstitch sewing machine having, in combination with other stitch forming devices, a hook needle, a locking thread supply case, a loop taker for passing each loop of needle thread about the thread case and for setting the stitch formed by the loop of needle thread previously engaged by the loop taker, a take-up and means 75 separate from the loop taker arranged to hold

momentarily each loop of needle thread from movement towards the work as it is being drawn by the take-up from the loop taker.

28. A lockstitch sewing machine having, in combination with other stitch forming devices, a hook needle, a shuttle, a locking thread case about which the shuttle passes each loop of needle thread and a take-up, a shuttle race, and means on the shuttle race arranged to enter and hold the needle loop as it is being drawn by the take-up from the shuttle towards the work.

29. A lockstitch sewing machine having, in combination with other stitch forming devices, a hook needle, a shuttle, a locking thread case about which the shuttle passes each loop of needle thread and a take-up, a shuttle race, a retaining finger on the shuttle race arranged to enter and hold the needle loop as it is being drawn by the take-up from the shuttle towards the work, and mechanism for actuating the retaining finger to release the needle loop before the needle draws the succeeding loop of needle thread through the work.

30. A lockstitch sewing machine having, in combination with other stitch forming devices, a hook needle, a loop taker, a locking thread case about which the loop taker passes each loop of needle thread, a take-up arranged to draw each needle loop from the loop taker towards the work, a needle looper and a finger separate from the loop taker for holding the loop of thread after passing over the loop taker while the looper is laying the thread in the hook of the needle and for releasing the needle loop before the threaded needle is withdrawn from the work.

31. A lockstitch sewing machine having, in combination with other stitch forming devices, a hook needle, a shuttle, a locking thread case about which the shuttle passes each loop of needle thread and a take-up, a shuttle race, a retaining finger on the shuttle race arranged to enter and hold the needle loop as it is being drawn from the shuttle towards the work, supporting means for the shuttle race comprising a carrier and a guideway along which the carrier may be shifted towards and from an operative position, and actuating connections for the retaining finger arranged to be disconnected when the shuttle race carrier is moved out of operative position.

32. A lockstitch sewing machine having, in combination with other stitch forming devices, a hook needle, a loop taker arranged when engaging each needle loop to pull the preceding needle loop into the work and set the stitch, a locking thread supply case about which the loop taker passes each loop of needle thread, means for imparting to said loop taker a plurality of rotations in each stitch forming cycle, each needle thread loop being transferred from the needle to the loop taker during one of said rotations, and a loop retaining finger acting during another of said rotations to hold the loop of needle thread after having passed over the thread case.

33. A lockstitch sewing machine having, in combination with other stitch forming devices, a hook needle, a loop taker arranged when engaging each needle loop to pull the preceding needle loop into the work and set the stitch, a locking thread supply case about which the loop taker passes each loop of needle thread, means for imparting to said loop taker a plurality of rotations in each stitch forming cycle, each needle thread loop being transferred from the needle to the loop taker during one of said ro-

tations, a loop retaining finger acting during another of said rotations to hold the loop of needle thread after having passed over the thread case, and mechanism for actuating the retaining finger to release the needle loop before the next loop of needle thread is passed over the thread case.

34. A lockstitch sewing machine having, in combination, stitch forming devices including a hook needle, a rotary loop taker and a locking thread supply case having a thread guiding abutment, thread deflecting means acting across the path of the locking thread adjacent the abutment to draw off from the supply in the thread case an amount for each stitch, a driving and stopping mechanism arranged when thrown into operation to bring the machine to rest with the needle disengaged from the work before the locking thread deflecting means acts, and means for gripping the locking thread between the deflecting means and the work to prevent movement of the locking thread from the work as the deflecting means acts at the beginning of a new seam.

35. A McKay type shoe sewing machine having, in combination, stitch-forming and work feeding devices including a straight hook needle, an awl, a rotatable work supporting horn, and a loop taker arranged when engaging each loop of needle thread to pull the preceding needle loop into the work and set the stitch formed by said preceding loop, and a presser-foot acting at the side of the work opposite to the horn to clamp the work before the awl engages the work and to release the work while each needle loop is being pulled into the work by the loop taker.

36. A McKay type shoe sewing machine having, in combination, stitch-forming and work-feeding devices including a straight hook needle, an awl, a rotatable work supporting horn, and a loop taker arranged when engaging each loop of needle thread to pull the preceding needle loop into the work and set the stitch formed by said preceding loop, a presser-foot acting at the side of the work opposite to the horn to clamp the work before the awl engages the work and to release the work while each needle loop is being pulled through the work by the loop taker, and means for raising the awl and for actuating the awl to feed the work while the work is released by the presser-foot.

37. A McKay type shoe sewing machine having, in combination, stitch-forming and work-feeding devices including a straight hook needle, a rotatable work supporting horn, a presser-foot, a shuttle and a take-up, a main sewing shaft, driving means therefor, separate trains of connections for actuating the needle and take-up from the sewing shaft, each train of connections comprising an element movable to disconnect the actuated device from the sewing shaft, means for disconnecting the sewing shaft from its driving means, and means for moving said elements upon disconnecting the driving means to bring the needle and take-up to rest with the needle disengaged from the work and the take-up near the end of its take-up stroke but sufficiently spaced therefrom to provide a short length of thread between the work and the end of the horn when the work is lifted from the horn.

38. A lockstitch shoe sewing machine having, in combination, stitch-forming and work-feeding devices including a straight hook needle, a rotary shuttle and a loop spreader, a main sewing shaft, driving means therefor, separate trains of

connections for actuating the needle, the shuttle and the loop spreader from the sewing shaft, the train of connections for actuating the needle and loop spreader comprising elements movable to disconnect the actuated devices from the sewing shaft, means for disconnecting the sewing shaft from its driving means, and means for moving said elements upon disconnecting the sewing shaft while the threaded needle is disengaged from the work before the loop spreader opens the needle loop to bring the threaded needle and loop spreader to rest during the continued rotation of the shuttle with the sewing shaft.

39. A McKay type shoe sewing machine having, in combination, a main base, a rotatable work supporting horn, an overhanging head frame, stitch-forming and work-feeding devices in the head frame including a straight hook needle, an awl, a main sewing shaft in the head, a take-up in the base close to the rotatable horn, a secondary shaft in the base for actuating the take-up in timed relation with the sewing shaft, driving means for said shafts, separate trains of connections comprising elements movable to disconnect the actuated devices from the sewing shaft and the take-up from the secondary shaft, means for disconnecting the shafts from the driving means, and control connections extending from the disconnectible elements driven from the secondary shaft to the disconnectible elements driven from the main shaft for moving said elements upon stopping the machine to bring the devices actuated by said trains to stopping positions.

40. A McKay type shoe sewing machine having, in combination, stitch forming and work

feeding devices including a hook needle, a rotatable shoe supporting horn having a needle receiving opening at its tip, and a rotary needle threading whirl in the horn comprising a lower bevel gear button having its smaller end uppermost and a separately formed upper bearing button secured to the upper end of the lower button to provide a shoulder to which bevel gear teeth of full depth on the lower button extend.

10 41. A McKay type shoe sewing machine having, in combination, stitch-forming and work feeding devices including a hook needle, a rotatable shoe supporting horn having a needle receiving opening at its tip, and a rotary needle 15 threading whirl in the horn comprising an upper button having an eccentric thread eye and a separately formed lower bevel gear button having a thread passage registering with the eye of the upper button and having the upper ends 20 of its bevel teeth covered beneath the outer edge of the upper button.

42. A McKay type shoe sewing machine having, in combination, a main frame, stitch-forming and work-feeding devices including a straight hook needle, a rotatable shoe supporting horn having a needle receiving opening at its tip, a needle threading whirl in the horn, a shaft for actuating the whirl mounted in the horn concentric to the axis of horn rotation, a shaft 25 in approximate alinement with the whirl actuating shaft for driving said whirl actuating shaft, and a flexible coupling between said shafts to permit adjustment of the horn when the needle does not enter properly into the needle opening.

BERNARD T. LEVEQUE.
